JAMES E. WILSON, OF NEW YORK, N. Y., ASSIGNOR TO THE NATIONAL LOCK WASHER CO., OF NEWARK, NEW JERSEY, A CORPORATION OF NEW JERSEY.

METHOD OF MAKING STEEL SPRING-WASHERS.

978,974.

Specification of Letters Patent. Patented Dec. 20, 1910.

Application filed March 15, 1910. Serial No. 549,421.

To all whom it may concern:

Be it known that I, JAMES E. WILSON, a citizen of the United States, residing at New York, county of New York, and State 5 of New York, have invented certain new and useful Improvements in Methods of Making Steel Spring-Washers; and I do declare the following to be a full, clear, and exact description of the invention, such as 10 will enable others skilled in the art to which it appertains to make and use the same.

My invention relates to certain new and useful improvements in and relating to method of making steel spring washers, and 15 consists in the novel steps and method hereinafter fully described and then particularly pointed out in the claim which concludes this description.

Heretofore, in the manufacture of spring washers of tempered steel made from severed convolutions of spiral coils such coils being wound from various forms of rod or wire the most common of which are of square or rectangular cross section, much 20 difficulty has been experienced owing to the fact that the sharp corners at the outer edges of these convolutions would crack or 25 fleck sufficient to invite fracture of the washers after they have been subjected to heat treatment such as hardening and tempering, and this flecking or cracking is due to the extensions or stretching of the steel in 30 winding it about the mandrel to form the spiral coil. No material flecking or cracking 35 appears at the inner edges of the spiral coil since the steel undergoes a swaging operation at these points more or less marked according to the temper of the rod since the latter may not be of uniform temper through- 40 out its length. Various expedients have been employed to obviate these difficulties, all more or less uncertain, and the object of my present improvement is to so form the rod or strip before winding as to prevent 45 any flecking or cracking at the outer edges of the completed coil. A keystone shape in cross section of rod has been used, but it does not obviate the slight ruptures heretofore mentioned.

50 Naturally, in winding steel stock on its edge, in order to form steel spring washers, the stretching upon the outer surfaces of

the coil thus formed is excessive, and the slight rupture at the outer edges of the coils proves a damage to the finished product; I 55 therefore form the rod, which may be square, rectangular or keystone in cross section, slightly round or convex at the corner portions which form the outer edges of the completed coil, and I have found by this 60 method that I eliminate all the difficulties heretofore mentioned, even when the material is almost too hard to wind.

In the accompanying drawing Figure 1 illustrates an edge elevation of the stock before winding and after the same has been 65 rolled in accordance with my method—Fig. 2 a cross section of such stock—Fig. 3 an elevation of the completed coil—Fig. 4 a cross section taken through one side of one 70 of the coils, and Fig. 5 is an isometric view of the spring washer formed by severing one of the coils.

Similar numbers of reference denote like parts in the several figures of the drawing. 75

In carrying out my improvement I roll the stock in such manner that it is preferably keystone shape in cross section and has convex surfaces which connect the side faces of the stock with the edges thereof, and in 80 the drawing the numeral 1 denotes the stock the side portions being denoted by the numeral 2, the outer edge by the numeral 3, and the inner edge by the numeral 4, while the convexities which connect the portions 85 2 with the portions 3, 4, are denoted by the numeral 5. I then wind this stock in the form of a spiral coil as indicated by the numeral 6 at Fig. 3, the inner edge 4 constituting the inner faces of the coils while 90 the outer edge 3 forms the outer surfaces of said coils. I prefer to round the edge portions at the surface 4 because a more symmetrical product is thereby obtained, although this rounding does not affect the 95 product in any way and these edges can be left sharp, if desired. During this process of winding the strip the inner or narrow edge thereof will be subjected to a swaging operation while the outer or wider edge will 100 undergo a stretching process such as hereinbefore referred to and explained, and the effect of this swaging and stretching is to slightly increase the thickness of the inner

edge 4 and to slightly decrease the thickness of the outer edge 3 and this will cause the side faces of the coils to become parallel and to be disposed at right angles to the inner 5 and outer faces as clearly shown at Fig. 4, while at the same time the edges will be slightly rounded.

As I said before, the rounding of the edges of the stock which forms the inner faces of 10 the coils is immaterial, but the rounding of the edge portions which appear at the outer faces of the coil is most important since all flecking or fracture incidental to the coiling is thereby prevented, so that when the washers are severed from the coil and subjected 15 to hardening and temper they will stand any amount of compression without breaking.

Having thus described my invention what

I claim as new and desire to secure by Letters Patent is:—

The herein described method of making steel spring washers, which consists in rolling the stock into a suitable shape in cross section and forming convex surfaces at edges thereof, winding such stock into the form of 25 a spiral coil with the convex surfaces at the outer edges of the convolutions of such coil, and finally severing each of said convolutions.

In testimony whereof I affix my signature 30 in presence of two witnesses.

JAMES E. WILSON.
